SNAP ACTING DEVICE

Fred B. Aubert, Detroit, Mich.

Application May 17, 1946, Serial No. 670,479

4 Claims. (Cl. 200—67)

1

This invention relates to new and useful improvements in snap-acting devices wherein a control means such as a valve or switch is quickly moved to or from a desired position.

An object of the invention is to provide a structure in which the control means is positively movable by a direct thrust thereby obviating sticking of the control means against movement.

Another object is to provide means to impart a shock or blow to the control means to dislodge it from a stuck position.

Another object is to provide a switch structure in which the contact members have a rolling action upon engagement thereby reducing the tendency of the contact members to fuse together.

The invention consists in the new and improved construction and combination of parts to be more fully described hereinafter and the novelty of which will be particularly pointed out and distinctly claimed.

In the accompanying drawings to be taken as a part of this specification, there are fully and clearly illustrated several preferred embodiments of the invention in which drawings:

Figure 1 is a view in side elevation of a snap acting switch mechanism having the casing cover member in section to show the switch structure embodying the invention,

Fig. 2 is a plan view in section on the line 2—2 of Fig. 1,

Fig. 3 is a view similar to Fig. 1; but showing the switch mechanism in an operating position,

Fig. 4 is an enlarged detail view showing the various stages of switch structure movement during the operation of the switch mechanism,

Fig. 5 is a detail view in section on the line 5—5 of Fig. 3,

Fig. 6 is a view in side elevation of a snap-acting valve mechanism also embodying the invention,

Fig. 7 is a view in side elevation of another form of switch structure and showing the parts in an intermediate position, and

Fig. 8 is a diagrammatic view of another form of snap switch mechanism.

Referring to the drawings and particularly Figs. 1 to 5, 1 designates a base member of electric insulating material preferably of elongated rectangular form having a peripheral seat or shoulder 2 to receive a hollow cover member 3 also of electric insulating material. The base member 1 is provided with an elevated supporting portion 4 adjacent one of its ends and which extends across the base member to provide a

2

mounting platform. Clamped to the top face of the platform 4 there is a furcated substantially rectangular resilient arm 5 of sheet metal which extends longitudinally of the base member and carries at its free end a control means or switch contact member 6. Also secured to the supporting platform 4 between the side arms of the switch arm 5 there is a rectangular elongated switch operating arm 7 of resilient sheet metal which is biased or urged by its inherent resiliency in a direction away from the base member. The arms 5 and 7 are preferably formed as by stamping from a single sheet of metal so that they are joined at their end portions which are 10 clamped by a plate 8 and screw 9 to the platform 4. The free end portion 10 of the arm 5 to which the contact member 6 is secured has intermediate the side arms or members, a tongue or projecting portion 11 directed toward the free 20 end of the operating arm 7 which also has at its free end a tongue or projecting portion 12. The arm 7 terminates in longitudinally spaced relation to the portion 10 and positioned therebetween there is a leaf spring 13 which is bowed 25 into an arcuate or substantially semi-circular form so that it is stressed for expansion longitudinally of the arms 5 and 7. The spring 13 is provided with parallel end slots to receive the projects 11 and 12 so that the spring 13 is pivotally connected to or fulcrumed on the arms 5 and 7. It will thus be seen that the arms 5 and 7 and the spring 13 provide three movable members which are stressed against each other to 30 form an over-center snap-acting mechanism which functions to quickly move the arm 5 when the point of connection between the arm 7 and spring 13 is moved through the line connecting the point of pivotal engagement of the spring 13 with the arm 5 and the point or line of connection of the arm 5 to the supporting platform 4. Cooperable with the contact member 6 there is a fixed switch contact member 14 which is carried by a metal bracket or plate member 15 which is supported on a post 16 of electric insulating material which is rigidly secured to the base member 1 by a hollow rivet 17 which projects from the underside of the base member and is internally screw threaded to receive a terminal or binding post screw 18.

The cover member 3 is provided with a stop member 19 which extends into the casing in overlying relation to the spring 13 and for engagement thereby. It will be noted that the stop member or pin 19 is positioned so that its point of engagement with the spring 13 is protected

by the curvature of the spring from straight line relation to the surface engagement or point of contact between the contact members 6 and 14. The surface portion of the spring 13 which is engageable with the stop member 19 is thus protected by the interposed spring portion 20 from any impingement thereon of particles of the switch contact material which might roughen the abutment engaging portion of the spring surface. Roughness of this spring portion surface would impede free slippage of the spring 13 on the abutment member 19. The cover member is rigidly secured in position by cross pins 21. Also carried by the cover member there is a switch operating thrust member or pin 22 having a button or head portion 23 within the switch casing and which rests on the top face of the arm 7. The pin 22 is guided for longitudinal reciprocation in a guide aperture 23a through the cover member 3 and may be operated by any desired means such as a bimetal heat motor, a relay armature or the like. The spring 13 has sufficient strength so that it acts by its inherent resilience under the force of the arm 7 to bow or bend the contact carrying arm 5 slightly downward in the position of Fig. 1 and such that when the parts are in the position of Fig. 3, the arm 5 will be bowed or bent slightly upward. This bowing or bending of the arm 5 results in the contact member 6 engaging the contact member 14 with a rolling action thereby reducing the tendency of the contact members to fuse and adhere to each other upon making contact. The clamping screw 9 is threaded into a metal tube 24 which projects from the underside of the base member 1 and receives a terminal screw or binding post 25 to receive one lead wire, the other lead wire being connected to the terminal 18.

The operation of the switch of Figs. 1 to 5 is as follows: When the pin 22 is depressed or moved inward into the casing against the force of the spring blade or the arm 7 and the expansive force of the spring 13, the point of engagement between the arm 7 and spring 13 will be moved downward or toward the arm 5. As the point of engagement between the arm 7 and spring 13 moves through the center position or crosses the plane of the arm 5, the force of the spring 13 will exert an upward component on the arm 5 and snap or quickly move the arm 5 into engagement with the contact member 14. The engagement of the contact member 6 with the contact member 14 will be as above noted, with a rolling action of the surface of the member 6 on the convex surface of the member 14. Because of the bias of the arm 7 to its position in Fig. 1, the arm 5 will be held in its contact making position only so long as the pin 22 is exerting sufficient force to overcome the force of the arm 7. When the force exerted on and through the pin 22 is released for switch breaking movement, the spring arm 7 will move from its full line position, Fig. 4, and when it crosses the line of the arm 5 there will be a downward component of force exerted by the spring 13 so that in normal operation when the arm 7 has moved say to the dash-dot line position, the spring 13 will be exerting sufficient force to move the arm 5 quickly downward to the switch open position as indicated by the dotted line of the arm 5 and contact member 6 in Fig. 4. In this dash-dot position of the arm 7, the spring 13 is also in the dash-dot position and has just come into engagement with the stop member 19. Accordingly any further upward movement of the

arm 7 will cause the spring 13 to cam or pivot on the stop member 19 so that there is a direct thrust of the spring 13 against the arm 5. This direct thrust by the spring 13 against the arm 5 is sufficient to break the contact member 6 away from the contact member 14 in the event that these contact members might have fused and stuck together. In addition to the direct thrust exerted by the spring 13, the force exerted by the inherent resilience of the arm 7 and the upward component of the end of the spring 13 engaging the arm 7, cause the spring 13 to strike against the abutment member with a sharp hammer blow which by its reaction through the spring 13 further serves to break apart the contact members 6 and 14 if they tend to stick together.

Referring to Fig. 6, 38 designates a valve casting having a valve port or passageway 31 controlled by a valve member 32 which is carried by an operation arm 33. A stop member 34 is preferably provided to limit opening of the valve member and travel of the arm 33 which is pivoted at 35. Cooperable with the arm 33 there is an expansion spring 36 which is laterally supported for longitudinal expansion and compression within a capsule or tubular member 37 having a reciprocal end portion 38 guided in the tubular portion and holding the spring 36 under compression. The spring supporting member 37 has its opposite ends terminating in conical tips which are received respectively in an arm or abutment member 39 rigid with the arm 33 and a flange or abutment member 40 rigid with a lever arm 41 pivoted at 42. The three members 33, 37 and 40 are therefore held under tension against each other by the force of the spring 36. The point of pivotal engagement 43 of the expansible member 37 with the abutment member 40 is positioned overcenter with respect to the line connecting the point 44 of pivotal engagement between the member 37 and abutment member 39 and the pivot 35 for the arm 33. Accordingly the spring 36 is exerting a component of its force to urge the valve member 32 against its seat and closing the port 31. The lever arm 41 is urged to the position of Fig. 6 by a spring 45 and is limited in its turning movement by the spring 45 by means of an adjustable stop member 46. Cooperable with the arm 41 there is an operating means 47 which may be as shown an electric heated bimetal heat motor which when heated by closure of the switch 48 will exert sufficient force to overcome the force of the spring 45 and move the point of engagement 43 downward and overcenter. As soon as the point 43 moves overcenter, the spring 36 will exert a component of its force in an upward direction on the arm 43 and snap or quickly move the valve member 32 to open position against its stop member 34. Upon movement of point 43 overcenter, the member 37 will laterally engage the stop or abutment member 40 with a hammer blow to dislodge the valve member and will thereupon rock or pivot on the member 40 so that the member 37 under the force of the heat motor 47 will exert a positive direct thrust against the lever arm 41 so that the valve member 32 will be positively moved toward open position and prevented from sticking in closed position. The return movement of the valve member 32 to closed position under the force of the spring 45 when the heat motor is deenergized and cools, will occur when the point 43 moves

through the line connecting the point 44 and the pivot point 42.

Referring to Fig. 7, there is a casing 50 having a fixed switch contact member 51 with which a moving contact member 52 cooperates. A lever arm 53 carries the contact member 52 and is pivotally supported on a fulcrum member or pin 54. Extending longitudinally of the arm 53 there is an operating arm 55 of resilient material which is bent or bowed as at 56 so that it tends to expand longitudinally. The arm 55 is also pivoted on the pin 54 and extends longitudinally of the arm 53 with its free end portion 57 terminating in spaced relation to an abutment portion 58 on the arm 53. Pivotally engaging the end portions 57 and 58 and held under compression therebetween there is an overcenter member 59 which upon overcenter movement for switch opening movement engages a stop member 60 carried by the casing 50. The overcenter member 59 is urged downward or to switch closing position by a coil spring 61 mounted and guided in the casing 50. Also cooperable with the member 59 there is an operating pin or thrust member 62 which is operable on inward movement to overcome the spring 61 and rotate the member 59 about the abutment member 60 so as to exert a positive direct thrust against the lever arm 53. The members 53, 55, 59 are held under tension against each other by the spring portion 56. In the position of the parts in Fig. 7, the thrust members 62 has moved the arm 59 upward from the position in which it is normally held by the spring 61, the position of the parts being an intermediate one such as would occur with sticking of the contact members 51 and 52 together with sufficient force so that the downward component of force of the spring portion 56 could not break them apart. Any further upward movement or inward movement of the member 62 into the casing will rock the member 59 upon the stop member 60 and force the member 52 away from its contact member 51.

Referring to Figure 8, the switch structure is generally similar to that of Fig. 1, but has the U-shaped or bowed leaf spring 70 inverted and has the contact carrying end portion 71 of the leaf spring or arm 72 bent or inclined to the main portion of the arm, so that its contact member 73 will engage the fixed contact member 74 with a sliding or wiping action. The spring 70 is held under compression between the arm 72 and the operating arm or leaf spring 75 which is biased in an upward direction or toward the contact member 74 so that it normally tends to position the spring 70 to urge the arm 72 out of contact making position or away from the contact member 74. Straddling the leaf spring 70, there is an operating means 76 which is a U-shaped lever pivoted off center, at 77, so that the leg 78 normally rests by gravity on the arm 75. The other leg 79 is engageable with the contact carrying lever 72 and the relation of the parts 75, 76 and 72 is such that when the contact members 73, 74 are in engagement, the legs 78 and 79 have simultaneous engagement with the arms 75 and 72 respectively, but only subsequent to movement of the arm 75 through center position on its contact separating movement. Therefore, if the contact members 73 and 74 tend to fuse or stick together, the force of the arm 75 is transmitted through the lever 76 and directly upon the lever 72 to move positively the contact member 73 away from the contact mem-

ber 74. Cooperable with the arm 75, there is an operating pin or plunger 80, guided in the casing 81 and operable to depress the arm 75 against its inherent resilience or bias. The pin 80 is operable to move the arm 75 over or through center so that the arm 75 is positioned on the opposite side of arm 72 from that shown in Fig. 8 and therefore moves the spring 70 over-center so that its reaction component acts upward on the arm 72 and snaps or quickly moves the contact member 73 into wiping or sliding engagement with the contact member 74. It may be noted that upon release of the pin 80, the spring 75 strikes the lever 76 and thus imparts a hammer blow to the arm 72 which in addition to the direct force exerted on the arm 72 through the lever 76 by the arm 75, assures the sudden breaking of contact between the contact members 73 and 74.

It will be apparent from the foregoing that there is provided a construction in which the movable control member has a direct thrust imparted thereto to eliminate sticking. By varying the position of the overcenter stop member or the length of the arms of lever 76, the thrust may be caused to occur either simultaneously with initial overcenter movement or subsequent to such initial movement in order to obtain the advantage of a hammer blow or shock imparted to the control member. It should be further noted, however, that the most desirable use of the principle of this invention is as a safety means and that as such the lever action and shock effect would not take place except when there is a failure of the contact members to separate upon normal overcenter action. The fact that the aforementioned use is deemed the most desirable one would not prevent other applications of the principle since by proper proportioning of parts said lever action could be made to take effect in any position of movement.

Having thus described the invention, what is claimed and is desired to be secured by Letters Patent of the United States is:

1. In a snap-acting mechanism, a pair of members, one of said members being resilient and of U-shaped form with one leg having pivotal engagement with the other of said pair of members, a third member extending substantially parallel to said other member and having pivotal engagement with the other leg of said one member, means supporting said third member and said other member for transverse movement of their one member engaging portions, an abutment member in the path of movement of the base portion of said one member, said other member being biased toward said abutment means and operable to move said one member thereagainst with an impact force thereby to transmit the pivotal effect of said impact to said third member, and a control member movable by said third member.

2. A snap-acting switch, comprising a base member, a supporting member spaced from and mounted on said base member, a contact member carried by said supporting member and facing said base member, a resilient arm having one end portion positioned between said supporting member and said base member and having its other end portion secured to said base member, a contact member carried by said arm and engageable with said first-named contact member, a resilient operating arm secured at one end portion to said base member adjacent said other end portion of said first-named arm and having

its other end portion biased to move away from said base member and being movable from one side to the other of said first-named arm, a leaf spring bowed concavely toward said base member and having its end portions positioned between and tensioned against said arms and having its point of engagement with said operating arm movable through center, a stop member rigid with said base member and positioned for engagement by the convex surface of said leaf spring upon movement of said operating arm to the contact member side of said first-named arm, said leaf spring having a portion of its surface interposed in the straight line path between the contact engaging surface of said first-named contact member and the portion of said leaf spring engaged by said stop member so that particles of contact member material will be prevented from impinging the stop member engaged portion of said leaf spring, and a plunger engageable with and operable to move said operating arm.

3. In a snap-acting mechanism, a resilient arm fixed at one end, a control member carried by the other end of said arm, a resilient operating arm fixed at one end adjacent said one end of said first-named arm and biased to move in one direction, said arms each having an abutment portion facing each other, a leaf spring bowed to U-shaped form and having its end portions engaging said abutment portions, a stop member positioned in the path of movement of and engageable by the external surface of the base portion of said spring, said operating arm acting to fulcrum said spring on said stop member to urge said first-named arm in a direction opposite to said one direction, means to move said operating arm against its bias and the point of engagement of said operating arm and said leaf spring

5 through center position, and said operating arm being operable upon release from said overcenter movement to move said leaf spring against said stop member with an impact to transmit to said first-named arm a shock force.

10 4. In a snap-acting mechanism, a pair of members, one of said members being resilient and of U-shaped form with one leg having pivotal engagement with the other of said pair of members, a third member extending substantially parallel to said other member and having pivotal engagement with the other of said pair of members, means supporting said third member and said other member for transverse movement of their 15 one member engaging portions, a control member movable by said third member by reaction of said one member against said other member, and means to produce and to transmit an impact force directly from said other member to said third member to supplement the reaction force of said one member.

Certificate of Correction

Patent No. 2,521,277

September 5, 1950

FRED B. AUBERT

It is hereby certified that error appears in the printed specification of the above numbered patent requiring correction as follows:

Column 8, line 12, strike out the words "of said pair of members" and insert instead *leg of said one member*;

and that the said Letters Patent should be read as corrected above, so that the same may conform to the record of the case in the Patent Office.

Signed and sealed this 28th day of November, A. D. 1950.
